UNITED STATES PATENT OFFICE.

ROSCOE W. STEPHENS, OF LOS ANGELES, CALIFORNIA.

COMBINATION DRILLING-RIG.

1,170,015.

Specification of Letters Patent.

Patented Feb. 1, 1916.

Application filed May 19, 1915. Serial No. 29,128.

To all whom it may concern:

Be it known that I, ROSCOE W. STEPHENS, a citizen of the United States, residing at Los Angeles, in the county of Los Angeles 5 and State of California, have invented a new and useful Combination Drilling-Rig, of which the following is a specification.

This invention relates to combination drilling rigs employed in the operations of standard and rotary drilling and a principal 10 object of this invention is to facilitate to the maximum the construction of wells and at the same time minimize the cost incident to said construction.

15 The advantages of this invention over other combination drilling rigs now in use in the oil fields are better understood when it is borne in mind that, in the construction of a well, the various operations of 20 standard and rotary drilling, lowering and raising of the tools, and lowering and raising of the casing and drill pipe are not performed in any fixed systematic order but are performed in an order that is dependent 25 upon the varying conditions arising from time to time from the start to the finish of the construction of the well. For instance, as an example, it is noted that the drilling of a well is often facilitated by employing 30 standard tools for working through some earth strata and by employing rotary tools for working through other earth strata.

From the foregoing it is clear that in order 35 to minimize the time and cost of construction of wells it is of advantage to make provision for quick substitution of one operation for another, for maximum simplicity of construction and operation and for reliability of operation. This invention is de- 40 signed to effect the foregoing.

This present invention differentiates from my prior invention of drilling rig patented to me August 11, 1914, No. 1,106,900, in that in said patent the construction was 45 such as to necessitate the use of gripping jaws to aid in driving the rotary table in order to dispense with the use of bevel gears employed for turning the turn table previous to said prior invention, whereas in 50 this present invention I am enabled to dispense with the gripping jaws and also with the bevel gears generally employed.

It is understood that the rotary drilling 55 table has to operate at relatively low speed and requires a powerful turning force to rotate it, such force being considerably be-

yond the transmitting capacity of any ordinary belt or frictional driving means. In order that the rotary table may be turned without the noise and expense incident to 60 the use of bevel gears and without the expense incident to the use of cable grips, that the table, bull wheel, draw works, walking-beam-operating crank arm and sand reel can all be operated from a single engine 65 and that the standard rig now in use in the oil fields may be utilized by merely adding thereto, I have provided a special construction including wire line transmission to the rotary table and have so arranged the va- 70 rious parts that said wire line transmission is effective to transmit the maximum amount of power from the engine to the turntable.

The accompanying drawings illustrate the 75 invention

Figure 1 is a plan view of the invention, a portion of the derrick and platform being broken away for clearness of illustration. Fig. 2 is a side elevation of Fig. 1.

There is provided a suitably constructed 80 frame 1 having at one end a platform 2 and a derrick 3 which is partly broken away in the drawings to contract the views. The platform end of the frame 1 is provided with posts 4 which rotatably support a bull 85 wheel 5 for the cable, not shown, used in raising and lowering the drilling tools, said bull wheel having a grooved band wheel 6 driven by an endless wire line 7 that is rove around a grooved band wheel 8 on a crank 90 shaft 9.

The crank shaft 9 is journaled in bearings 10 mounted on standards 11 of the frame 1, and said crank shaft is provided at one end with a crank arm 12 designed to be 95 connected to the usual walking beam, not shown, for reciprocating the standard drilling tools. The crank shaft 9 is provided with a second band wheel 13 turned by a wire line 14, which is rove around a grooved 100 sheave 15 adapted to be thrown into and out of operation by a clutch 16 which is mounted on a power shaft 17 driven by an engine 18. The power shaft 17 is journaled in bearings 19 supported by uprights 20 of 105 the frame 1, and said shaft is provided with a second grooved sheave 21 designed to be thrown into and out of operation with the power shaft 17 by a second clutch 22.

The sheave 21 drives a wire line 23 which 110 is rove around the grooved band wheel 24 of a rotary table 25 designed to turn the ro-

- tary drilling tools, and one lead of the wire line 23 passes in a straight line from the sheave 21 to the band wheel 24, and the other lead of said wire line passes in a straight line from the sheave 21 to an idler 26 mounted on an upright 27 of the frame 1, and said other lead passes diagonally relative to the long axis of the frame from said idler to the band wheel 24, said idler thus 10 bending one lead of the wire line to one side of the frame. One strand of the wire line 23 is rove around a tightening idler 28, which is mounted on a standard 29 of the frame 1.
- 15 The crank shaft 9 is provided with a sprocket wheel 30 driving a sprocket chain 31 which engages a sprocket wheel 32 mounted on a shaft 33 of the draw works designated in general by the character 34, said 20 draw works having the customary high and low speed gearing 35, 36. The band wheel 13 is provided adjacent its periphery with the friction wheel 37 of a sand reel 38, said friction wheel 37 being adapted to be thrown 25 into and out of engagement with the band wheel 13 by operation of the arm 39 in the usual manner.
- 30 The clutches 16, 22 are operated by clutch rods 40, 41 respectively connected by crank arms 42 to transversely extending shafts 43 journaled in bearings 44 mounted on the frame 1, one end of said shafts being provided with operating levers 45, and the crank arms 42 are so arranged that when 35 the operating levers 45 are turned in one direction, the clutches 16, 22 are thrown out of commission and that when the operating levers are moved in the opposite direction, the clutches are thrown into commission.
- 40 From the foregoing it is clear that in practical operation assuming that the engine 18 is running and that the operator desires to operate rotary drilling tools, he will throw the clutch 22 into commission to drive 45 the wire line 23 and thereby turn the rotary table and the drilling tools. If the operator desires to operate the standard drilling tools, he will throw the clutch 20 out of commission and the clutch 16 into commission to 50 drive the wire line 14 and the crank 12 so as to reciprocate the drilling tools in a manner well understood. When the operator desires to draw the casing or drill pipe, he will do so in the usual manner through 55 the agency of the draw works 34, which are being driven by reason of the clutch 16 being in commission. If the operator wishes to raise or lower the tools, he will put the bull wheel into operation through the 60 agency of the clutch 16, and will proceed in the usual manner to raise or lower the tools, it being understood that the bull wheel and draw works may be operated in either direction by appropriate operation of the engine-reversing mechanism well understood 65

and therefore not necessary to be shown in the drawings.

By the construction described above, I am enabled to effect the various operations in the construction of a well by a single engine 70 instead of employing two engines as heretofore, and have also otherwise simplified the drilling rig so as to minimize the liability of said rig getting out of order.

It is noted that the above described construction makes it possible to use but one hoist instead of two and also makes it possible to drive the rotary table, crank shaft and bull wheel through the agency of reliable and comparatively inexpensive wire 75 line transmission in lieu of unreliable rope 80 belts, expensive sprocket wheels and chain, and expensive bevel gearing heretofore in use, thus minimizing the cost of construction 85 and maintenance and at the same time insuring to a maximum extent against delays in 90 performing the various operations incident to the construction of wells.

What I claim is:

1. A combination drilling rig comprising 90 a frame, a power shaft mounted at one end of the frame, an engine to drive said power shaft, sheaves, means on the power shaft to throw the sheaves into and out of operation, a bull wheel mounted at the opposite 95 end of said frame, a crank shaft mounted on the frame between the bull wheel and power shaft and provided with a crank arm for connection to a walking beam to operate standard tools, two band wheels on said 100 crank shaft, a rotary table between the bull wheel and crank shaft provided with a band wheel, a wire line rove around one of the sheaves and one of the band wheels, a second wire line rove around the second band 105 wheel and bull wheel, a third wire line rove around the second sheave and around the band wheel of the rotary table, draw works between the crank shaft and rotary table, and driving connections between the draw 110 works and crank shaft.

2. A combination drilling rig comprising 115 a frame, a derrick at one end of the frame, a bull wheel mounted transversely on the frame at one side of the derrick, draw works mounted transversely on the frame at another side of the derrick diametrically opposite the bull wheel, a rotary table between the bull wheel and draw works, a power shaft mounted transversely at the other end 120 of the frame, an engine to turn said power shaft, sheaves, means operative to throw either one of the sheaves into operative relation to the power shaft, a crank shaft mounted transversely on the frame between 125 the draw works and power shaft, two wheels on the crank shaft, driving connections at one side of the frame between one of said wheels and the bull wheel, other driving connections at said side of the frame be- 130

tween the second wheel and one of the sheaves, and a wire line at the other side of the frame rove around the other sheave and the rotary table.

5 3. A combination drilling rig comprising a frame, a power shaft mounted at one end of the frame, an engine to drive said power shaft, sheaves, means on the power shaft to throw the sheaves into and out of operation, 10 a bull wheel mounted at the opposite end of said frame, a crank shaft mounted on the frame between the bull wheel and power shaft and provided with a crank arm for connection to a walking beam to operate 15 standard tools, two band wheels on said crank shaft, a rotary table between the bull wheel and crank shaft provided with a band wheel, a wire line rove around one of the sheaves and around one of the band wheels, 20 a second wire line rove around the second band wheel and bull wheel, a third wire line

rove around the second sheave and around the band wheel of the rotary table, an idler 25 rotatively mounted near one side of the frame, one lead of said third wire line passing in a straight line from its sheave to the band wheel of the rotary table and the other lead of said third wire line passing in a straight line from its sheave to said idler and thence diagonally relative to the long 30 axis of the frame from said idler to the band wheel of the rotary table, draw works between the crank shaft and rotary table, and driving connections between the draw works and crank shaft.

In testimony whereof I have hereunto set my hand at Los Angeles, California, this 13th day of May, 1915.

ROSCOE W. STEPHENS.

In presence of—

LORA M. BOWERS,
FREDERICK E. LYNN.
